UNITED STATES PATENT OFFICE

PRESTON W. GROUNDS, OF TERRE HAUTE, INDIANA, ASSIGNOR TO AMERICAN ART WOOD PRODUCTS CORP., OF TERRE HAUTE, INDIANA, A CORPORATION OF INDIANA

DESIGN FOR A LAMP OR ANALOGOUS ARTICLE

Application filed November 7, 1931. Serial No. 41,657. Term of patent 3½ years.

To all whom it may concern:

Be it known that I, PRESTON W. GROUNDS, a citizen of the United States, residing at Terre Haute, in the county of Vigo and State of Indiana, have invented a new, original, and ornamental Design for a Lamp or Analogous Article, of which the following is a specification, reference being had to the accompanying drawings forming part thereof.

Fig. 2 is a view in side elevation with the shade removed.

Fig. 3 is a diagrammatic plan view, with the shade, lamp bulb and socket removed.

I claim:

The ornamental design for a lamp or analogous article, as shown and described.

PRESTON W. GROUNDS.
